His Attorney.

UNITED STATES PATENT OFFICE.

JOHN EATON, OF SCHENECTADY, NEW YORK, ASSIGNEE TO GENERAL ELECTRIC COMPANY, A CORPORATION OF NEW YORK.

CONTROL-SWITCH.

1,350,924.

Specification of Letters Patent. Patented Aug. 24, 1920.

Application filed July 26, 1918. Serial No. 246,801.

To all whom it may concern:

Be it known that I, JOHN EATON, a subject of the King of Great Britain, residing at Schenectady, county of Schenectady, State of New York, have invented certain new and useful Improvements in Control-Switches, of which the following is a specification.

My invention relates to electric circuit controllers and has for its object the provision of an improved device of this character whereby electric circuits may be changed in a simple and efficient manner.

My invention relates more specifically to a circuit controller having a number of positions in which it is possible to move from one contact position to any one of a number of other contact positions without making contact at the intermediate position or positions.

In carrying out my invention, I provide a rotatable contact member which is normally in a position so that its contacts will not engage with stationary contacts when the member is rotated. To adjust the controller to any position the member is turned to the proper position whereupon the member is moved out of its normal position and into engaging position with the stationary contacts.

In the accompanying drawings illustrating my invention Figure 1 is a side view of the complete device, Fig. 2 is a sectional view thereof, Fig. 3 is a perspective view of a portion of the controller frame; and Fig. 4 shows a detail of the hand wheel.

Referring to the drawings 10 represents an elongated frame preferably composed of strips of insulating material 11, held in place by end pieces 12. Located centrally of this frame is a shaft 13 having bearings in the end pieces and turned by means of a hand wheel 14. Located on the frame and concentrically with the shaft are stationary contacts 15, which may be distributed longitudinally thereof as shown. Mounted upon the shaft are a plurality of contacts 16, 17 and 18 which are arranged to engage with the stationary contacts. As shown, the contacts are of the double break type held in place by clamps 19. A spring 20 forces the shaft longitudinally so that the contacts 16, 17 and 18 will not engage with the stationary contacts when the shaft is turned. For locating the shaft in various

contact positions I provide projections 21 in a disk 22 secured to the shaft, which projections coöperate with notches 23 in the stationary frame 12. The shaft is of course cylindrical where it passes through the frame 12 so that the shaft can be turned. Unless, therefore, the projections are opposite the notches in the end plate the shaft cannot be moved forward. In order to move the shaft longitudinally against the spring pressure to make contact when the shaft is rotated to its proper position, I have shown for purposes of illustration a cam 24 which upon being turned will force the shaft by engaging a projection 25 thereon.

In operation it will be seen that when the hand wheel 14 is turned to the proper position to make the desired connections, and the cam is turned to force the shaft longitudinally, the contacts on the shaft will engage the stationary contacts. When the cam is turned to release the shaft the latter will move backward out of contact. I have not attempted to show any means for operating the cam since this may be done in any desired manner depending upon the location of the controller and the use to which it is put.

It will be seen that I have provided a circuit controller in which while there are a number of consecutive contact positions it may be moved to any one of them without making contact at intermediate positions.

While I have described my invention as embodying a concrete structure and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What I claim as new and desire to secure by Letters Patent of the United States, is:

1. A circuit controller comprising a plurality of sets of radially disposed stationary contacts mounted on a support for the same with intervening spaces between the sets of contacts, a shaft having a plurality of contacts arranged longitudinally thereof rotatable to positions adjacent the stationary contacts but normally out of engage-

ment therewith during its movement, and means for forcing said shaft longitudinally from its normal position into engagement with any of the fixed contacts when it reaches a position adjacent thereto.

2. A circuit controller comprising a plurality of sets of radially disposed stationary contacts mounted on a support for the same with intervening spaces between the sets of contacts, a shaft having a plurality of contacts arranged longitudinally thereof rotatable to positions adjacent the stationary contacts but normally out of engagement therewith during its movement, and a cam arranged to force the shaft longitudinally from its normal position into engagement with any of the fixed contacts when it reaches a position adjacent thereto.

3. A circuit controller comprising an elongated frame, a rotatable shaft extending centrally of said frame, contacts mounted upon the frame longitudinally of the shaft and concentrically therewith, contacts upon said shaft rotatable to positions adjacent the stationary contacts, a spring for forcing the shaft longitudinally so that its contacts will be out of engaging relation with the stationary contacts during the movement of the shaft, and means for forcing the shaft longitudinally against the spring into engagement with any of the fixed contacts when it reaches a position adjacent thereto.

In witness whereof, I have hereunto set my hand this 24th day of July, 1918.

JOHN EATON.
